UNITED STATES PATENT OFFICE.

JOHN T. DONNELL, OF ST. LOUIS, MISSOURI.

DESIGN FOR A SOUVENIR HAT-PIN.

SPECIFICATION forming part of Design No. 35,661, dated February 4, 1902.

Application filed December 12, 1901. Serial No. 85,711. Term of patent 3½ years.

To all whom it may concern:

Be it known that I, JOHN T. DONNELL, a citizen of the United States, and a resident of St. Louis, Missouri, have invented and produced a new and original Design for Souvenir Hat-Pins, of which the following is a specification, reference being had to the drawings, forming part thereof.

Figure 1 is a view in elevation of the souvenir hat-pin, showing my new design on an enlarged scale. Fig. 2 is a cross-section at the horizontal center of the globe, parts being omitted which are not on a line with the center.

As shown in the drawings, the leading or

material features of my new design consist of the lattice-work globe 3, having a bank 4 at the equatorial center, the conical lattice-work 5, supporting the globe, and the archwork 6, supporting the conical portion 5. The filigreed portion 7 extends downwardly from the archwork 6, connecting to the pin 8.

I claim—

The design for a souvenir hat-pin, substantially as herein shown and described.

JOHN T. DONNELL.
